(57) **CLAIM**

The ornamental design for an aircraft body, as shown and described.

DESCRIPTION

FIG. 1 is a top/right side perspective view of the aircraft body.

FIG. 2 is a rear view of the aircraft body.

FIG. 3 is a front view of the aircraft body.

FIG. 4 is a left side view of the aircraft body.

FIG. 5 is a right side view of the aircraft body.

FIG. 6 is a top view of the aircraft body; and,

FIG. 7 is a bottom view of the aircraft body.

The broken lines shown in FIGS. 1-7 represent portions of the aircraft body that form no part of the claim.

1 Claim, 7 Drawing Sheets

FIG. 2

FIG. 3

FIG. 4

FIG. 5

FIG. 6
